Primary Examiner — Karen E Eldridge Powers(74) *Attorney, Agent, or Firm* — Daniel V. Thompson(57) **CLAIM**

The ornamental design for a heat-resistant kitchenware tool, as shown and described.

DESCRIPTION

FIG. 1 is a front-facing perspective view of the heat-resistant kitchenware tool showing my new design;

FIG. 2 is a top plan view thereof;

FIG. 3 is a bottom plan view thereof;

FIG. 4 is a left-side elevational view thereof;

FIG. 5 is a right-side elevational view thereof;

FIG. 6 is a front-side elevational view thereof; and,

FIG. 7 is a back-side elevational view thereof.
